J. H. HAWES, OF BOSTON, AND GEORGE H. BLISS, OF WEST STOCKBRIDGE,
MASSACHUSETTS.

Letters Patent No. 77,281, dated April 28, 1868.

IMPROVED MACHINE FOR CLEANING EMERY.

The Schedule referred to in these Letters Patent and making part of the same.

TO ALL WHOM IT MAY CONCERN:

Be it known that we, J. H. HAWES, of Boston, in the county of Suffolk, and State of Massachusetts, and GEORGE H. BLISS, of West Stockbridge, in the county of Berkshire, in the same State, have invented a new and useful Improvement for Rubbing and Separating Stone and other Foreign Matter from Emery, applicable also to other purposes, of which the following is a full, clear, and exact description, reference being had to the accompanying drawing, forming part of this specification, and which represents a mainly central vertical section of a machine or apparatus constructed in accordance with our improvement.

Emery, as it is usually supplied to the various trades which use the article, is seldom or never free from stone or other foreign matter, and it has been found very difficult to extract or separate such foreign substances therefrom. The object of this our invention is to accomplish such result in a most simple and efficient manner; and our invention consists in a peculiarly-constructed machine for the purpose, comprising among other features a cylinder, preferably set vertical or thereabouts, through which the emery, after it has been crushed to a suitable size, is passed, and crooked or serpentine rubber arranged to rotate therein, and serving to reduce or pulverize into a very fine dust, the stone and other foreign matter mixed up with the emery, as the latter is run through the cylinder, so that the separation may afterwards easily be effected by an ordinary sifting process; said machine also embracing a disk or flange below the rubber, at the lower end of the cylinder, for retarding the discharge of the emery from the latter in advance of the stone or other foreign matter being pulverized, which disk may have interposed between it and the lower end of the cylinder any suitable discharge-regulating device.

Referring to the accompanying drawing, A is the cylinder, which may be of hopper-form at its top, into and down which the emery is fed and passed. This cylinder is shown as erected upon a receiving-box, B, into which it opens. Arranged to pass centrally up through the cylinder A, and say through the box B, is a shaft, C, crooked or twisted where it passes through the cylinder to form a serpentine rubber, or having a rubber, D, of such character secured to and carried by it. This rubber or its shaft is made to rotate, say, by any suitable gear arranged below the box B, or otherwise disposed, the same working in suitable bearings at either end. Below the lower end of the cylinder A, at a short distance from it, is arranged a disk, E, which may be carried by the shaft C, and which serves to retard the discharge or keep the emery in the cylinder till separated, or the stone or other foreign matter is fully pulverized; and between this disk and the lower end of the cylinder is or may be located a discharge-regulating lever, F, or other suitable device, adjustable from the exterior, and operating to more or less check the discharge, as required. Around the shaft C, where it passes through the box B, may be set a tube, G, to protect the gear and work below from emery getting therein.

The rubber D thus constructed and operating, effectually serves, and in an expeditious manner, to reduce to a fine dry dust, stone or other foreign matter mixed up with the emery, so that on sifting the contents of the box B, all such foreign matter is readily extracted.

What is here claimed, or desired to be secured by Letters Patent, is—

1. The combination, with the cylinder A, of the rotating rubber D, of serpentine form, substantially as specified.

2. The combination of the plate or disk E with the cylinder A and rubber D, for operation together as described.

J. H. HAWES,
GEO. H. BLISS.
